TRIP MECHANISM FOR PRINTING-PRESSES.

1,107,843.

Specification of Letters Patent. Patented Aug. 18, 1914.

Application filed March 25, 1914. Serial No. 827,039.

To all whom it may concern:

Be it known that I, CHARLES JAMES ROBERTSON, a subject of the King of England, residing at Taunton, in the county of Bristol and State of Massachusetts, have invented certain new and useful Improvements in Trip Mechanism for Printing-Presses, of which the following is a specification.

The primary object of this invention is to provide, in that class of printing presses employing a transfer surface for imparting to the material to be printed the design received from an inked form, such an impression trip mechanism that there may be a trip for the impression of the inked form upon the transfer surface and also a separate and distinct trip that may be differently timed for the impression of the transfer surface upon the material to be printed, and at the same time disturbing the position of the axis of the transfer-surface-carrying member only. This latter provision avoids complications in sheet handling and inking arrangements which would ensue should either the sheet carrying member or the form carrying member be disturbed in position in the act of tripping, the term "tripping" being employed herein in the sense of interrupting the regular contact between the cylinders to intermit the normal printing operation.

In the accompanying drawing and in the detailed description based thereon is set forth in a diagrammatic manner and by way of illustration only a preferred embodiment of the invention, it being understood that the invention is susceptible of embodiment in other and varied constructional forms without departure from its essence or material sacrifice of its advantages.

The form of the invention illustrated in the drawings is that of a single revolution cylinder rotary offset printing press wherein sheets of paper and the like are printed through the medium of an offset cylinder from a design carried by a lithographic metal plate upon a form carrying cylinder.

Referring to the drawings, 1 designates the form carrying cylinder, 2 the offset cylinder having the usual rubber blanket, and 3 the impression or paper cylinder. The ink is supplied to the form cylinder from a fountain by ink rolls 4 as is usual and provision is made, though not shown, for damp-

pening in the usual manner. The sheets of paper are fed from feed board at 5 to grippers 6 on the impression cylinder 3, printed by rubber transfer and thence given up to delivery cylinder 7 and delivered, all as usual. It will be noted that the sheet is shown as occupying about 160° of the cylinder 3, the rest of the time being used to feed sheets.

In cases where all the cylinders, as in the example shown, are single revolution, when printing is progressing no trip or throw off mechanism is needed, the three cylinders all rotating on fixed axes, but in inking-up, and particularly in cases of mis-fed sheets, the impression needs throwing off. A convenient and accessible arrangement of the three cylinders, as that shown, gives the result that the period of time during which the inked form is transferring the design to the rubber transfer surface is not coincident with the period of time during which the design is being printed upon the paper. Consequently it is desirable, when the operator finds a misfeed entails a trip that, whereas the rubber must not print that revolution, yet the plate must complete the design on the rubber so that the first sheet printed after the trip shall be perfect. That is to say, the two operations of transferring and printing being sequential, the trip and return of each should be sequential. Therefore, the two separate trips use two different directions of movement of the offset cylinder axis. The path of movement of the axis of the offset cylinder in one direction is so selected as to keep its distance relation constant to the form cylinder and varying to the impression cylinder for the paper trip and the other path of its movement constant to the impression cylinder and varying to the form cylinder for the plate trip. The cam rollers 8 and 9 are used one for each trip to operate each a separate rockshaft 10, 11 and each to move the offset cylinder 2 in one of its paths of movement independent of the other path.

In the drawings a paper impression trip cam 12 is shown upon the impression cylinder 3 operating the cam lever 13 which is fulcrumed at 14 to the framing, while a plate impression trip cam 15 is shown upon the form cylinder 1, operating the cam lever 16 fulcrumed at 17 to the framing. For

simplicity of drawing and explanation, I have shown the paper trip cam on the impression cylinder and the plate trip cam on the form cylinder. But it is to be noted that 5 one cam can readily be used for both, the only requisite being that the respective cam levers and their cam rollers be located around the center of the cam so that the one cam may act upon the two trips one after 10 the other with the necessary number of degrees rotation between. In such a case the links would need slight rearranging so that if "impression on" is low part on one cam for one trip, it would be the same for the 15 other, as the links are shown "impression off" low dwell of paper-impression-trip cam corresponds to "impression off" high dwell of plate-impression-trip cam.

The impression cylinder 3 is journaled in 20 boxes 18 mounted in the framing and adjusted to and from offset cylinder 2 by screws 19, to alter the amount of pressure between rubber and paper. In operation the impression cylinder boxes 18 are fixed. The 25 plate cylinder 1 is journaled in boxes 20, mounted in the framing and adjusted to and from the offset cylinder 2 by screws 21 to alter the amount of pressure between plate and rubber. In operation the form cylinder 30 boxes 20 are fixed.

The offset cylinder 2 is journaled in eccentrics 22 employed to throw off and on the impression between the rubber and the paper and the centers of the outside of these eccentrics 22 are located relatively to the line of centers of the form cylinder 1 and the offset cylinder 2 so that the path of movement of the axis of the offset cylinder 2 is normal to this line of centers, and thus offset cylinder 2 40 moves to and from the impression cylinder 3 without altering its distance from the form or plate cylinder 1, when moved by eccentrics 22. The eccentrics 22 in turn are mounted in sliding boxes 23 sliding in the 45 frame in a direction normal to the line of centers of the impression cylinder 3 and the offset cylinder 2 so that the cylinder 2 may be moved to and from the cylinder 1 without altering its distance from the cylinder 3. 50 This sliding is effected by the action of the eccentrics 24, formed with trunnions journaled in brackets 25 bolted to the frame, and upon these eccentrics 24 are boxes 26 sliding in slots in the boxes 23 which latter slots 55 are at right angles to the direction of sliding of the box 23 in the framing.

Levers 27, links 28, and levers 29 connect the plate eccentrics 24 on both sides of the press to rock shaft 11 across the press. Levers 60 30, links 31, and levers 32 connect the paper eccentrics 22 on both sides of the press to the rock shaft 10 across the press. Link 33 connects the paper cam lever 13 to a lever 33^a which oscillates freely upon the rock shaft 10 and has integral with it a stud 34.

Link 35 connects plate cam lever 16 to a lever 36 which oscillates freely upon rock shaft 11. This lever 36 has integral with it and oscillating together with it a stud 37. Now it will be seen that upon providing for coupling and uncoupling, (at will but in proper time) the stud 34 on lever 33^a with the rock shaft 10 and the stud 37 on lever 36 with rock shaft 11, a connection will be set up between each of the impression trip cams and 75 its respective eccentric so as to trip that impression independently of the others. Also fastened to the rock shafts 10 and 11 are impression restoring abutments 38 and 39, and preferably integral with these impression restoring abutments 38 and 39 are levers 40 and 41 carrying studs 42 and 43 upon which are hung loosely, under control of gravity, impression removing abutments 44 and 45, weighted at 46 and 47 and having 80 tails 48 and 49 as shown. When cam 12 moves stud 34 to contact with the impression restoring abutment 38, impression removing abutment 44 will fall under the influence of weight 46 and, swinging upon 85 stud 42, will engage the stud 34 closely between the two abutments 38 and 44 provided there is then no obstacle in the way of the tail 48. If this coupling occurs, it is evident that movement from cam 12 will be 90 transmitted through link 33 and stud 34 to abutment 44 and the impression between paper and rubber will be tripped by the rocking of shaft 10 and the movement of eccentric 22. In the same way when cam 15 100 moves stud 37 to contact with 39 impression removing abutment 45 will fall by reason of the weight 47 swinging on 43 and will engage stud 37 closely between 39 and 45 provided no obstacle is then in the way of the 105 tail 49, and if this coupling occurs the cam 15 will, through link 35, stud 37, and abutment 45, cause impression between plate and rubber to be tripped by the rocking of shaft 11 and moving of sliding boxes 23. 110

Pivoted to the frame, adjacent shaft 10, is a doubled ended lever 50 carrying a stud 51 which at times acts as an obstacle in the way of the tail 48 on impression removing abutment 44 and prevents the same from falling, and also pivoted to the frame adjacent shaft 11 is a double ended lever 52 carrying stud 53 which at times acts as the obstacle in the way of the tail 49 on impression removing abutment 45 and prevents it from 115 falling.

Passing through feeder platform 54 and guided by it is a pedal 55 for the operator to use in tripping impression. When he finds he has misfed a sheet, he depresses the 120 pedal and holds his foot on till cam 12 has moved stud 34 over against impression restoring abutment 38 when, obstacle stud 51 having by his action been removed, the impression removing abutment 44 falls and 125 130

engages 34 between 38 and 44 and cam 12 proceeds to trip impression. It will be noted that at any instant while printing is progressing normally the pedal 55 may be 5 depressed and obstacle stud 51 and obstacle stud 53 will be removed and impression trip abutments 44 and 45 will be free to fall as soon as the respective cam 12 or 15 carries the stud 34 or 37 clear as its own time 10 arrives. The exigencies of misfeeding will determine the time of depressing the pedal 55 near enough to avoid depressing it too late to trip the paper yet early enough to trip the plate.

15 The pedal 55 is on the upper end of the pedal rod 56 passing through and guided by the feeder platform 54 and also passing through a lug 57 on frame. This lug 57 acts as an abutment for the spring 58 which 20 pushes up on a collar 59 fast to the rod 56 and tends to restore the pedal 55 to its upper limit as fixed by the collar 60. The lower end of pedal rod 56 is articulated to the free end of lever 61 which in turn is 25 fast to short shaft 62 passing through the frame. The inner end of shaft 62 is provided with a lever 63 thus forming a bell crank. Rod 64 connects double ended lever 50 to bell crank 63 and this rod 64 is of 30 fixed length. Rod 65 connects to the lower end of double ended lever 52 by a fixed stud but connects to the lower end of bell crank 63 by such a connection that it is of fixed length in tension but collapsible in compression by reason of its sliding in a slot 66 through bell crank 63 under action of a spring 67 and a collar 68. The stop 69 fixes its length under tension.

When in tripping the operator depresses 40 the pedal and holds it down till abutment 44 and then abutment 45 have dropped and started moving their cylinders and then releases it, the spring 58 being stronger than the spring 67, will try to restore pedal to 45 its upper position against stop 60. But at this time the cam 12 will have the paper impression tripped, the lever 33* and stud 34 will have swung anti-clockwise to their limit, when, although the abutment 44 will 50 then engage the stud 34, yet its tail 48 will clear the stud 51 even with pedal entirely up because of the shape of the bite out of tail 48. Thus double ended lever 50 is free to return at this time to its "pedal up" position shown without its influencing the trip 55 of the paper impression eccentric, for the rotation of the cylinder journal in eccentric boxes 22 will maintain a pressure between the stud 34 and the abutment 44. Thus 44 can only disconnect when the "impression on" part of cam 12 has control of the position of the cylinder axis, or when cylinder 2 is printing on cylinder 3. Similarly 45 can only disconnect when the "impression on" part of cam 15 has control of the posi-

tion of the cylinder axis or when cylinder 1 is printing on cylinder 2. At the time of releasing the pedal, also, the force of moving cylinder 2 and its sliding boxes 23 will come upon the abutment 45 and the spring 58 will 70 not be able to lift 45 out of engagement, and therefore spring 67 will be collapsed and store energy to lift 45 out when its time will have come, which will be when the "impression on" dwell of the plate impression 75 removing cam 15 is acting on cam roller 9.

I claim:

1. In tripping mechanism for printing presses, the combination of a form cylinder, an impression cylinder, an interposed offset cylinder, and means for tripping the offset cylinder from the companion cylinders in timed sequence to intermit the normal printing operation, substantially as described.
2. In tripping mechanism for printing 85 presses, the combination of a form cylinder, an impression cylinder, an interposed offset cylinder, the form cylinder and impression cylinder having fixed axes of rotation, and the offset cylinder shiftable toward and from the companion cylinders, and means for tripping the offset cylinder from the companion cylinders in timed sequence to intermit the normal printing operation, substantially as described.
3. In tripping mechanism for printing 95 presses, the combination of a form cylinder and an impression cylinder having fixed axes of rotation, an offset cylinder shiftable toward and from each of the companion cylinders along a line normal to a line joining its axis with the axis of the other of said companion cylinders, and means for so shifting the offset cylinder as to trip its operative relation to the companion cylinders in timed 105 sequence, substantially as described.
4. In tripping mechanism for printing 110 presses, the combination of a form cylinder and an impression cylinder having fixed axes of rotation, an offset cylinder shiftable toward and from each of the companion cylinders along a line normal to a line joining its axis with the axis of the other of said companion cylinders, and means for so shifting the offset cylinder as to trip its operative 115 relation to the impression cylinder and to the form cylinder in timed sequence and in the order named, substantially as described.
5. In tripping mechanism for printing 120 presses, the combination of a form cylinder, an impression cylinder, an interposed offset cylinder, the form cylinder and impression cylinder having fixed axes of rotation, and the offset cylinder shiftable toward and from the companion cylinders, and means for tripping the offset cylinder from the companion cylinders in timed sequence, said tripping means comprising a pair of eccentricities each arranged to shift the axis of the offset cylinder in one direction, a pair of 130

- normally inactive rock shafts, gearing operatively connecting each of said eccentrics with one of the rock shafts, a set of rock-shaft-driving mechanism actuated in timed relation to the rotation of each of the form and impression cylinders, and means under the control of the operator to couple each set of driving mechanism to its rock shaft, substantially as described.

10. In tripping mechanism for printing presses, the combination of a form cylinder, an impression cylinder, an interposed offset cylinder, the form cylinder and impression cylinder having fixed axes of rotation, and the offset cylinder shiftable toward and from the companion cylinders, and means for tripping the offset cylinder from the companion cylinders in timed sequence, said tripping means comprising a pair of eccentrics each arranged to shift the axis of the offset cylinder in one direction, a pair of normally inactive rock shafts, gearing operatively connecting each of said eccentrics with one of the rock shafts, a set of rock-shaft-driving mechanism actuated in timed relation to the rotation of each of the form and impression cylinders, and means under the control of the operator to couple each set of driving mechanism to its rock shaft, the rock shaft driving mechanisms each including an oscillatory stud, and the coupling means including a latch adapted to engage the stud as an abutment, substantially as described.

35. 7. In tripping mechanism for printing presses, the combination of a form cylinder, an impression cylinder, an interposed offset cylinder, the form cylinder and impression cylinder having fixed axes of rotation, and the offset cylinder shiftable toward and from the companion cylinders, and means for tripping the offset cylinder from the companion cylinders in timed sequence, said tripping means comprising a pair of eccentrics each arranged to shift the axis of the offset cylinder in one direction, a pair of normally inactive rock shafts, gearing operatively connecting each of said eccentrics with one of the rock shafts, a set of rock-shaft-driving mechanisms each actuated in timed relation to the rotation of each of the form and impression cylinders, and means under the control of the operator to couple each set of driving mechanisms to its rock shaft, the rock shaft driving mechanisms each including an oscillatory stud, and the coupling means including a latch carried by the shaft and adapted to engage the stud as an abutment, and a catch acting to normally hold the latch inoperative, substantially as described.

8. In tripping mechanism for printing presses, the combination of a form cylinder, an impression cylinder, an offset cylinder, the form cylinder and the impression cylinder having fixed axes of rotation, the offset cylinder mounted in journal boxes slideable in a direction normal to the line joining its axis with the axis of one of the companion cylinders and shiftable in said box in a direction normal to a line joining its axis with the axis of the other of said companion cylinders, and means for so shifting the offset cylinder in its journal boxes and so sliding the journal boxes as to trip the operative relation of the offset cylinder to its companion cylinders in timed sequence, substantially as described.

9. In tripping mechanism for printing presses, the combination of a form cylinder, an impression cylinder, an offset cylinder, the form cylinder and the impression cylinders having fixed axes of rotation, the offset cylinder mounted in journal boxes slideable in a direction normal to the line joining its axis with the axis of one of the companion cylinders and shiftable in said box in a direction normal to a line joining its axis with the axis of the other of said companion cylinders, a pair of eccentrics one arranged to slide the journal boxes of the offset cylinder and the other to shift the axis of the cylinder in the boxes, and means under the control of the operator to actuate the eccentrics to trip the operative relation of the offset cylinder to the impression cylinder and to the form cylinder in timed sequence and in the order named, substantially as described.

10. In tripping mechanism for printing presses, the combination of a form cylinder, an impression cylinder, an offset cylinder, the form cylinder and the impression cylinders having fixed axes of rotation, the offset cylinder mounted in journal boxes slideable in a direction normal to the line joining its axis with the axis of one of the companion cylinders and shiftable in said box in a direction normal to a line joining its axis with the axis of the other of said companion cylinders, a pair of eccentrics one arranged to slide the journal boxes of the offset cylinder and the other to shift the axis of the cylinder in the boxes, a pair of normally inactive rock shafts, gearing operatively connecting each of said eccentrics with one of the rock shafts, a set of rock-shaft-driving mechanism actuated in timed relation to the rotation of each of the form and impression cylinders, and means under the control of the operator to couple each set of driving mechanism to its rock shaft, whereby to trip the operative relation of the offset cylinder to each of the companion cylinders in timed sequence, substantially as described.

11. In tripping mechanism for printing presses, the combination of a form cylinder, an impression cylinder, an offset cylinder, the form cylinder and the impression cylinders having fixed axes of rotation, the offset

cylinder mounted in journal boxes slidable in a direction normal to the line joining its axis with the axis of one of the companion cylinders and shiftable in said box in a direction normal to a line joining its axis with the axis of the other of said companion cylinders, a pair of eccentrics one arranged to slide the journal boxes of the offset cylinder and the other to shift the axis of the cylinder in the boxes, a pair of normally inactive rock shafts, gearing operatively connecting each of said eccentrics with one of the rock shafts, a set of rock-shaft-driving mechanism cam actuated in timed relation to the rotation of each of the form and impression cylinders, and means under the control of the operator to couple each set of driving mechanism to its rock shaft whereby to trip the

operative relation of the offset cylinder to the impression cylinder and to the form cylinder in timed sequence and in the order named, the rock-shaft-driving mechanisms each including an oscillatory stud, and the coupling means including a latch carried by the shaft and adapted to engage the stud as an abutment, and a catch acting to normally hold the latch inoperative, substantially as described.

In testimony whereof I have hereunto signed my name in the presence of two subscribers witnesses.

CHARLES J. ROBERTSON.
